UNITED STATES PATENT OFFICE

LEONARD ST. CLAIR COOPER, OF HOLLYWOOD, CALIFORNIA

FOLDABLE BOX

Application filed March 26, 1928. Serial No. 264,942.

This invention relates to foldable boxes of a type adapted to fold up into a small space when not in use so as to be readily transported from place to place, and which when 5 out-folded or set up for use will form a rigid, shock-resisting structure adapted for shipment of easily crushed articles such for instance as drummers' samples of ladies' hats, fancy paper confections, stuffed and mounted 10 birds, etc.

The objects of my invention are to provide a box of the kind outlined above which will have great rigidity, be very compact when folded and which may be used repeatedly 15 without injury.

Briefly described my invention comprises a box structure in which a main frame constitutes the edges and corners of the box, and lattice sections form the six sides of the box. 20 The main frame is made of bars, preferably metal, pivoted together at the corners so that it may be collapsed to bring all the bars substantially to parallel relation, while the lattice sides are pivoted so that they may be similarly collapsed when removed from the main frame, though if desired the whole box may be collapsed to flat form of about the area of two sides even with the lattice sides in position.

30 The lattice sides are made of slats, preferably metal, pivoted together with the slats running diagonally of the box when in place so as to firmly brace the main frame against collapse. The lattice sides preferably snap 35 into place on the main frame by means of snap fasteners on the corners and/or elsewhere.

The box when all set up is a rigid, strong 40 lattice structure able to withstand severe shocks such as would result in shipping the boxes by common carriers, and in order to protect its contents against dust or dampness a waterproof cover is provided, and which preferably encloses the entire skeleton 45 box structure, or if desired the "cover" may be small enough to be inserted within the skeleton box, or in other words a lining for protection of whatever is shipped in the box.

In the drawings Fig. 1 is a perspective view 50 of my foldable box all set up.

Fig. 2 is an enlarged plan view of the main frame of the box folded.

Fig. 3 is a plan view of one side grille of the box folded.

Fig. 4 is a sectional view through a pivoted corner joint of the main frame.

Fig. 5 is a sectional view through one corner of one of the lattice sides.

Fig. 6 is a perspective view of a cloth or rubber lining or cover for the skeleton box 60 of Fig. 1.

Figs. 7 to 13 inclusive are diagrammatic sketches showing various steps in setting up or folding the box with main features thereof given the same designating numerals as used 65 in Figs. 1 and 2 so as to preserve the identity therewith.

In further detail and with respect to Fig. 1 the box comprises six side frames each made of four flat strips or bars overlapping and 70 pivoted together at the corners. The two forward or vertical sides in Fig. 1 are respectively formed of the four strips A, B, C, D and E, F, G, H and the corner pivots for the two sides respectively 1, 2, 3, 4 and 5, 6, 7, 8. 75 The top side of the box is similarly formed by the four bars, I, J, K, L pivoted at the corners at 9, 10, 11, 12.

The six sides of the box are all similar to the three described and the vertical sides are 80 all hinged one to the other at the corners as indicated at 13, 14, 15 so that if there were no top and bottom sides the frame could be crushed flat by reason of these corner hinges.

The top and bottom wall frames are hinged 85 respectively at 16 and 17 to adjacent vertical sides so as to swing parallel with and against the sides, and the top and bottom are also provided with pivotally connected spring clips as at 18 at their free edges adapted to engage and lock with the bar of the side when the box is set up.

Thus when the top and bottom sides are 90 swung over against the vertical sides the box is open on top and bottom as shown in Fig. 8 95 and the structure may then be collapsed to flat position as indicated progressively in Figs. 9 and 10.

To form side walls for the box I provide 100 a foldable lattice frame designated M, N, O

respectively for the three sides shown in Fig. 1.

The lattice is preferably constructed of spaced diagonally arranged flat metal strips 5 overlapping and pivoted together as indicated so that separately they will collapse to the shape shown in Fig. 3.

When extended, the latticed sides each form a grille which is detachably secured in 10 place on the main frame of the box, preferably inside of the same. A convenient method of securing the frames in place is by means of snap catches such as used for fastening gloves, the four corners of the grille being 15 provided with the socket part 19 of the fastener and the corner pivots of the frame are extended inwardly as at 20 to form the button to snap within the socket.

Also while describing this construction at 20 attention is called to a few extra snap buttons or other attaching devices projecting inwardly of the box from the grille walls. These are indicated at 21 in Figs. 1 and 5 and serve for securing an article in place in the box 25 so it will not shift, or provide for suspending a fragile commodity within the box.

The waterproof cover 22 for the box shown in Fig. 6 is preferably made of oil cloth or treated canvas or the like and provided with an overlapping flap 23 fitted with fastening devices as at 24.

In the diagrams 7 to 13, 7 shows the box completely set up as in Fig. 1, Figs. 8, 9, 10 the steps of collapsing it flat with grille walls in 35 place, whereas Figs. 11, 12, 13 show the separate collapsing of the frame when grilles are removed. The showing of Fig. 11 may be considered the same as that of Fig. 9 with grilles removed and the corners P, Q, pulled 40 upward. Fig. 12 shows the upper corners fully extended, and Fig. 13 the folded members of Fig. 12 again folded one upon the other on the hinges 14 of Fig. 3, thus bringing the finally folded frame to the condition 45 shown in Fig. 2.

I claim:

1. A foldable box comprising open framework sides hingedly connected together, and lattice wall panels adapted to be detachably 50 secured to the frame-work sides, said lattice wall panels each comprising a series of overlapping slats pivotally connected whereby the structure may be folded together.

2. A box comprising a rectangular skeleton 55 frame outlining the twelve edges of the box, and a lattice panel for each side of the box detachably secured in place, the six sides of the box thus outlined by said skeleton frame provided at each corner with means whereby 60 the skeleton frame for each side may be folded with frame members substantially parallel, four connecting sides of the box being permanently linked together by said means, and the two remaining sides respectively at one edge permanently linked by said 65

means to one edge of one of said four sides, and detachably at the other edge, and said lattice panel being pivotally connected in its parts whereby it may be folded.

3. In a foldable box provided with lattice 70 wall panels forming the sides thereof, said lattice wall panels comprising a series of overlapping slats, means extending through said slats from the outside of the box to the inside thereof at points of overlap of said 75 slats pivotally connecting said slats overlapping together and devices projecting the inner ends each of said pivotal connections whereby an article for shipment may be suspended in the box.
